[57] CLAIM

The ornamental design for a container for data storage disks, as shown and described.

DESCRIPTION

FIG. 1 is a top, left front perspective view of a container for data storage disks showing our new design in an exploded condition;

FIG. 2 is a front elevational view thereof, the rear elevational view being identical thereto;

FIG. 3 is a left side elevational view thereof, the right side elevational view being identical thereto;

FIG. 4 is a top plan view thereof;

FIG. 5 is a bottom plan view thereof;

FIG. 6 is a perspective view thereof with the cover removed and the pocket portion in expanded state; and, FIG. 7 is a left side elevational view with the cover removed and the pocket portion in expanded state, the right side elevational view being identical thereto.

FIG. 1

FIG. 2

FIG. 3

FIG. 4

FIG. 5

FIG. 6

FIG. 7
